UNITED STATES PATENT OFFICE

ERNEST A. PUTNAM, OF IOWA CITY, IOWA

INTERNAL-COMBUSTION ENGINE

Application filed May 2, 1927. Serial No. 188,300.

The present invention relates to an internal combustion engine of the sleeve valve type and has for its principal object to provide improved means for actuating the sleeve valve so that during their cycles of rotation the speed thereof will be intermittently advanced and retarded to insure the proper opening and closing of the valve in an efficient and reliable manner.

10 Another very important object of the invention resides in the provision of a rotary valve gas engine of the four cycle type wherein the valve is in the form of a rotating sleeve and has a spiral gear formed thereon meshing with another spiral gear mounted on a shaft and means for imparting continuous uniform rotary motion to the shaft and means for reciprocating the shaft back and forth so as to impart an irregular rotary motion 20 to the valve in a predetermined manner so that the valve will open and close quickly and will remain open a proper length of time to insure proper intake and proper exhaust.

A still further very important object of 25 the invention lies in the provision of an improved structure of this nature which is simple, compact, convenient, thoroughly efficient and reliable in its operation, inexpensive to construct, and otherwise well adapted 30 to the purpose for which it is designed.

With the above and numerous other objects in view as will appear as the description proceeds, the invention resides in certain novel features of construction, and in 35 the combination and arrangement of parts as will be hereinafter more fully described and claimed.

In the drawing:

Figure 1 is a vertical transverse section 40 through the engine embodying the features of my invention.

Figure 2 is a horizontal section taken substantially on the line 2-2 of Figure 1 looking downwardly;

45 Figures 3, 4, 5 and 6 are horizontal sections taken through one of the cylinders and valves substantially on the line A-A of Figure 1 showing the valve in different positions.

Referring to the drawing in detail it will 50 be seen that the numeral 5 denotes the crank

case having a crank shaft 6 rotatably mounted therein and formed at one end with a spiral gear 7. Anti-friction bearing members 8 are mounted in the crank case and slidably and rotatably support a shaft 9 having spiral gears 10 formed thereon one for each cylinder 11 of the engine. A chain and sprocket mechanism 13 operatively connects the shaft 6 with the shaft 9 for rotating the shaft 9 at one fourth crank shaft speed. The sprocket 14 of the chain and sprocket mechanism 13 is splined on the shaft 9 and is rotatably mounted in a bearing 15. A bracket 16 in one end of the crank case rockably supports a rocker arm 17 which has a link connection 18 with one end of the shaft 9. A spiral gear 19 is rotatably mounted in the crank case having a shaft 20 with a crank 21 thereon with which one end of the rocker arm 17 is pivotally engaged. It will be seen from the above description that as the crank shaft rotates continuous uniform rotary motion is imparted to the shaft 9 and simultaneously said shaft 9 is reciprocated 70 back and forth through the gears 7 and 19 and crank 21, the rocker arm 17, and the link 18. Connecting rods 23 are mounted in the usual well known manner between the cranks in the crank shaft 6 and pistons 24 which are mounted for rectilinear movement 80 in sleeve 25 rotatable in the cylinders 11. The lower ends of the sleeve 25 are provided with worm gears 26 meshing with worm gears 10. Anti-friction bearing members 27 are mounted in the crank case to engage the 85 under surface of the worm gears 26 to support the sleeve 25 in the cylinders. The cylinders are provided with intake openings 28 and exhaust openings 29 while the sleeve valves are provided with openings 30 registerable with openings 28 and 29.

The valve when disposed in the figure shown in Figure 3 is closed and the piston is in the top of the cylinder ready to begin the firing stroke. In Figure 4, the valve is shown ready to open for the exhaust as the piston reaches the bottom of the cylinder. In Figure 5, the valve is shown when the piston has again reached the top and is about to move downwardly on its intake 100

stroke and in Figure 6 the valve is shown after the intake stroke.

From the above detailed description it will be seen that the rotor or sleeve rotates the entire 360 degrees during a four stroke cycle movement of the piston. This makes it possible for a single port opening to open and close the exhaust port, also the intake port during this period. This has an advantage of placing the port openings on the outer cylinder wall for the advancement or retarding a degree for proper working conditions. In the drawings the parts are proportioned and operatively connected together so that the gear 19 makes four complete revolutions for a four stroke cycle or for two complete revolutions of the crank shaft 6. By this method the valve openings is advanced the distance desired to insure quick opening and also the valve is returned to its proper position for the next valve opening. Two revolutions of the gear 19 occur during the period of compression and firing stroke. It is possible by this method to give the valve a quick opening, also a longer period of opening, completely scavenging the cylinder of burnt gases. From the above it will be seen that each sleeve valve makes one complete revolution for each four strokes of the engine and during such revolution causes an acceleration in three phases, namely; pausing once in front of the exhaust port, once in front of the inlet port and a third time at about the beginning of the downward explosion stroke.

It is thought that the construction, operation, and advantages of this invention will now be quite apparent to those skilled in this art without a more detailed description thereof. The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention what I claim as new is:

1. In an engine of the class described, a cylinder having a pair of spaced openings one for exhaust and the other for intake, a sleeve rotatable in the cylinder and having an opening registerable with the first mentioned opening, and means for imparting variable rotary motion to the sleeve so that the opening of the sleeve will register quickly with the openings of the cylinder and will remain in registry therewith for a predetermined length of time and then move quickly out of registry therewith, said means comprising a spiral gear on the sleeve, a shaft, means for slidably and rotatably mounting the shaft, a spiral gear on the shaft meshing with the spiral gear on the sleeve, means for imparting constant rotary motion to the shaft, and means for reciprocating the shaft.

2. In an engine of the class described, a cylinder having a pair of spaced openings one for exhaust and the other for intake, a sleeve rotatable in the cylinder and having an opening registerable with the first mentioned opening, and means for imparting variable rotary motion to the sleeve so that the opening of the sleeve will register quickly with the openings of the cylinder and will remain in registry therewith for a predetermined length of time and then move quickly out of registry therewith, said means comprising a spiral gear on the sleeve, a shaft, means for mounting the shaft so that the same may be rotated and reciprocated, a spiral gear on the shaft meshing with the first spiral gear, means for imparting constant rotary motion to the shaft, a rocker arm, means for rocking the rocker arm, and means operatively connecting the rocker arm with the shaft for reciprocating said shaft.

3. In an engine of the class described, a cylinder, a crank case connected to the cylinder, a crank shaft rotatable in the crank case, a sleeve rotatable in the cylinder, a piston in the sleeve, a connecting rod between the piston and the crank shaft, said sleeve having a spiral gear mounted thereon, a shaft, means for rotatably and slidably mounting the last mentioned shaft in the crank case, a spiral gear on the last mentioned shaft meshing with the first mentioned spiral gear, means for rotating the last mentioned shaft from the crank shaft in a predetermined ratio and means operable from the crank shaft for reciprocating the second mentioned shaft.

4. In an internal combustion engine, a cylinder, a sleeve in said cylinder, means adapted to impart uniform rotation to said sleeve, and means for increasing and decreasing the rate of said rotation at predetermined intervals.

5. In an internal combustion engine, a cylinder, a sleeve in said cylinder, means connected to the crank shaft of said engine adapted to impart uniform rotation to said sleeve, and a second means cooperating with said shaft for varying said rate of rotation of said sleeve.

6. In an internal combustion engine, a cylinder, a sleeve rotatable in said cylinder, means adapted to impart a uniform rotation to said sleeve, and means for introducing a cyclic change of motion into said uniform rotation.

7. In an internal combustion engine, a cylinder, a sleeve rotatable in said cylinder, means adapted to impart a uniform motion

to said sleeve, and means for introducing a change of motion into said uniform motion.

8. In an internal combustion engine, a cylinder, a sleeve rotatable in said cylinder, means for imparting a uniform rotation to said sleeve, said means including a shaft, and means for reciprocating said shaft for varying the speed of rotation of said sleeve.

10. In an internal combustion engine, a cylinder, a sleeve rotatable in said cylinder, means for rotating said sleeve, said means including teeth on said sleeve, a shaft, a gear on said shaft meshing with the teeth 15 on said sleeve for rotating the same, and means for reciprocating said shaft.

10. In an internal combustion engine, a crank shaft, a cylinder, a sleeve rotatable in said cylinder, means for rotating said sleeve, 20 said means including teeth on said sleeve, a shaft, a gear on said shaft, meshing with said teeth on said sleeve, and means operable from the crank shaft for reciprocating said second mentioned shaft.

25 In testimony whereof I affix my signature.
ERNEST A. PUTNAM.
